UNITED STATES PATENT OFFICE.

JAMES JOHNSTON CURRIE, OF BONNINGTON FALLS, BRITISH COLUMBIA, CANADA.

WASHBOARD.

1,356,973.

Specification of Letters Patent. Patented Oct. 26, 1920.

Application filed January 9, 1918. Serial No. 211,095.

To all whom it may concern:

Be it known that I, JAMES J. CURRIE, a subject of the King of Great Britain, residing at Bonnington Falls, in the Province of 5 British Columbia and Dominion of Canada, have invented certain new and useful Improvements in Washboards; and I do hereby declare the following to be a full, clear, and exact description of the invention, such 10 as will enable others skilled in the art to which it appertains to make and use the same.

This invention relates to improvements in washboards.

15 The object of this invention is to improve the construction of washboards so that in the process of washing clothes they may be readily rubbed upon the soap, obviating the necessity of the soap being rubbed upon the 20 clothes.

A further object of this invention is to construct the rubbing surface of the board of corrugated or fluted material such as zinc, metal, glass or the like and the fluting or 25 the corrugations extending diagonally from one side of the board to the opposite side and the lower downwardly inclined ends terminating into a vertical recess formed in the side of the board to permit the dirty 30 water to readily drain from the corrugations or fluted rubbing surface of the board.

A still further object of this invention is to improve the construction of washboards and to provide the head thereof with an 35 opening which constitutes the soap holding means, whereby cakes of soap may be fitted in the opening and the clothes rubbed over the soap until all of the soap is completely used thereby preventing waste in the throwing 40 away of the soap after the same has been worn down as is now done in rubbing the soap on the clothes.

A further object of this invention is to provide a washboard with a novel soap holding means whereby the soap may be prevented from continually slipping into the water, and making it possible to use up the 45 whole bar of soap, so arranging the soap that the clothes may be readily rubbed over 50 the soap prior to rubbing them on the washing surface.

A still further object of this invention is to provide a washboard of this character, which will be simple, practical and comparatively inexpensive in construction, and 55

one that can be manufactured and sold at a low cost.

With these and other objects in view, the invention consists in the novel combination and arrangement of parts hereinafter more 60 fully described and set forth in the claim hereto appended.

In the drawings—

Figure 1 is a front elevation of my improved washboard made in accordance with 65 this invention,

Fig. 2 is a vertical sectional view of the same,

Fig. 3 is a detail sectional view,

Fig. 4 is a transverse sectional view of the 70 washboard.

Fig. 5 is a perspective view of the wedge-shaped member, and

Fig. 6 is a perspective view of the guide 75 which receives the wedge-shaped member.

Like numerals of references designate corresponding parts in all the figures of the drawings.

Referring to the drawings, the numeral 5 designates standards or supporting members of the washboard and are connected adjacent their lower ends by the transverse brace 6. A transverse head brace 7 connects the upper ends of the standards together and mounted between the opposing 80 faces of the members 5 adjacent the upper ends thereof is the board 8 which constitutes the soap holder. The board 8 is provided centrally with a longitudinally extending rectangular opening 9 in which the 85 soap is adapted to be positioned.

A rubbing surface 10 is corrugated or fluted as at 11 and it is constructed of zinc, metal, glass, or any other material suitable for the purpose. The flutes or corrugations 95 11 of the rubbing board 10 extend diagonally from one standard to the other and at their lower ends communicate with a vertical groove 12 formed in the inner face of one standard 5 thereby permitting the water 100 to run down off of the corrugations or fluted portions 11 of the scrubbing board 10 into the groove where it may be readily drained into the tub in which the washboard is positioned.

105 A plurality of relatively spaced vertically extending retaining wires 13 are secured to the front face of the board 8 and span the opening 9. These wires limit the soap in its outward movement and position 110

one face of the soap flush with the highest point of the corrugations 11 which forms the rubbing surface of the board. It can be seen that it is only necessary when the 5 soap is in position to rub the clothes on the rubbing surface and pull the same up over the soap in the opening 9 of the soap holder thereby obviating the necessity of rubbing the soap on the clothes as the clothes can 10 be rubbed over the soap by virtue of this construction.

A member 14 is secured to the back of the board adjacent the top thereof. This member is wedge-shaped and has an upwardly 15 and outwardly inclined rear wall 15, the side edges of which are bent at right angles thereto to provide the flanges 15' and the terminals of the flanges are bent outwardly at right angles to the side flanges to pro- 20 vide attaching members 16. The attaching members 16 are secured to the rear surface of the board as at 17 and the lower edge of the rear wall 15 terminates below the plane of the bottom wall of the opening 25 9 and in close proximity to the rear wall of the washboard rubbing surface 10.

A wedge-shaped member 18 has its side edges bent at right angles thereto and tapered to provide guide flanges 19 so as 30 to permit the wedge-shaped member to be readily slid in the socket member to cause the wall 18 to engage the rear face of the soap designated A in the drawings to urge the same outwardly in contact with the 35 wires 13 thereby to arrange the face of the soap against the wires in a plane at the highest point of the corrugations or fluted portions 11 of the rubbing surface 10 and readily permit the clothes to be moved over 40 the surface of the soap when it is desired to use the same.

A handle 20 has one end secured to the wall 18 of the wedge-shaped member and extends upwardly beyond the upper edge 45 thereof and facilitates placing of the wedge-shaped member in the wedge-shaped socket when the device is in use.

It will be apparent that the slot 9 is of sufficient length to permit of the use of two 50 bars of soap arranged therein and that the

wall 18 of the socket member engages the rear surface of the soap and constantly urges the same in contact with the wires 13 flush with the surface of the corrugations or fluted portions 11 of the scrubbing sur- 55 face 10. It is only necessary when the soap has become worn thin and is in the plane of the walls of the slot 9 to remove the wedge-shaped member 18 from the socket member and place new cakes of soap against the 60 rear face of the old cake of soap already in the soap holder, and urge the wedge-shaped member into the socket receiving member 14, and the new cakes of soap will urge the original or initial cakes of soap out against 65 the wires until it is all consumed and the new cakes will then be substituted therefor.

Having thus described my invention, what I claim is:

In a washboard, a rubbing member, a 70 board mounted adjacent the upper end thereof and provided with an opening for receiving a cake of soap, wires extending vertically across said opening at the side thereof adjacent the rubbing surface of said 75 rubbing member for limiting movement of a cake of soap through the opening, a member mounted at the opposite side of the board from said wires and secured at its edges to the board at the side edges of the 80 opening and provided with a downwardly and inwardly inclined outer wall spaced at its upper and lower edges from the adjacent surface of the board, and a wedge member fitting into the same and provided 85 with end flanges inclined similarly to the inclination of the outer wall of the member carried by said board, said wedge member being provided with a substantially vertical inner wall for engaging a cake of 90 soap placed in said opening so as to exert constant pressure thereon for holding the soap in close contact with said wires.

In testimony whereof I affix my signature in presence of two witnesses.

JAMES JOHNSTON CURRIE.
